SHIPPING CRATE FOR LIVESTOCK

Arthur O. Manger, Philadelphia, Pa., and Edward A. Tomlin, Jr., Hampton, Conn., assignors, by mesne assignments, to Rathborne, Hair & Ridgway Box Co., Chicago, Ill., a corporation of Illinois

Application December 30, 1948, Serial No. 68,196

6 Claims. (Cl. 119—18)

1

This invention relates to improvements in shipping containers or crates for livestock. More particularly, it pertains to a shipping crate for livestock having an improved type of removable feed and water trough combination and the provision of such structure is a principal object of the invention.

More specifically, the invention has to do with a wire bound shipping crate for livestock, especially poultry, with a removable longitudinal partition arranged along the floor of the crate between its end walls and in adjacently spaced relation with respect to one of the side walls to provide a feed trough and a removable transverse partition whose ends are mounted in slots or apertures in the side wall structure, the transverse partition being slotted interlockingly to engage the longitudinal partition to hold the latter in erect and spaced apart position with respect to the adjacent side wall.

Another object of the invention is to provide a crate such as that above described wherein there is utilized in combination with the removable partition a removable watering trough disposed between one of the side walls and the longitudinal partition which provides the feed trough with a transverse partition which is slotted interlockingly to engage the longitudinal partition and also a wall of the watering trough to hold both the trough and the longitudinal partition in position.

Other objects of the invention will in part be obvious and will in part appear hereinafter.

For a fuller understanding of the nature and objects of the invention reference should be had to the following detailed description taken in connection with the accompanying drawings, in which:

Fig. 1 is a perspective view, partially broken away, illustrating a wire bound shipping crate embodying the feed and water trough arrangement of the present invention;

Fig. 2 is a plan view of the structure shown in Fig. 1; and

Figs. 3 and 4 are, respectively, enlarged views in section along the lines 3—3 and 4—4 of Fig. 2, looking in the direction of the arrows.

Various types of shipping crates for livestock, such as started and grown live poultry, game or ornamental birds, small animals—wild or domestic—have appeared on the market. A popular conventional crate of this type is the wire bound shipping crate which needs no detailed description. Such a crate is shown in Fig. 1 wherein wood slats or pieces of veneer are bound

together by longitudinally spaced apart continuous wires to provide what is known as a mat with mitered end cleats running along opposite marginal edges. Sections of such mat are folded around slatted side walls to provide a container or shipping crate as indicated generally at 10 in the drawings.

More particularly referring to Fig. 1, there is shown end walls 11 provided by spaced apart horizontally disposed slats, a bottom 12 also provided by slats, or broad veneer sheets of board material, closely abutting each other, and all of which are secured together by longitudinally spaced apart wires 13 held to the slats in any suitable manner such as, for example, by means of staples.

The above mentioned mitered cleats secured to the mat are shown at 14 and 15.

The cover, shown generally at 16, is a continuation of the mat and is of similar construction to the bottom. The wires 13 extend around the corner and are secured thereto by means of staples. The cover is thus hinged and the ends of the wires connected thereto can be made to engage loops 17 in the other ends of the wire upwardly projecting from the end walls to secure the cover in closed position.

The side walls 18 are provided by vertically disposed spaced apart slats providing apertures secured together by a top side wall strip 19, nailed or otherwise secured to the vertical slats, and a bottom side wall piece 20 similarly secured to the bottom of the vertical slats. The side walls are affixed to the inner sides of the cleats 14 and 15 in any suitable manner such as by nailing them thereto.

Crates of the foregoing type have been used for transporting livestock and, in particular, poultry, and it has long been recognized that an improved adaptation of such a crate which would embody feed and water troughs as a part of the structure would be a distinct advantage. Such a construction is provided by means of the present invention.

The improvement of the present invention will be seen in the provision of a novel type of structural arrangement of transverse partitions indicated generally at 21 and of a longitudinal partition indicated generally at 22. The longitudinal partition consists of a removable strip or slat 23 arranged along the floor or bottom 12 of the crate between the end walls and preferably adjacently spaced from one of the side walls. This strip is in no wise affixed to the end walls or bottom by nailing or in any other manner to

make it a permanent part of the structure. In its spaced apart position it provides a feed trough along one wall although it will be apparent that such feed troughs can be provided along opposite side walls. The other wall of the feed trough, that is, the strip or slat 20, is the structure permanently secured to the bottoms of the vertically disposed slats which comprise the side walls 18. Preferably the slats 20 are broader than the top slats 19 along the ends of the vertical slats forming the side walls 18 and are of a width commensurate with the slat 23.

To maintain the slat 23 in spaced apart relation with respect to the slat 20, there is utilized a novel structural arrangement of transverse or cross partition above referred to as being indicated generally at 21. This preferably comprises two spaced apart slats 24 and 25 nailed or otherwise secured to vertical pieces or legs 26 disposed inwardly from the marginal edges of the slats 24 and 25. The lower slat 25 has a slot or cut-out portion 27. It also has a cut-out section removed from one end to provide a depending element 28 which fits into the trough area provided by the longitudinal partition 23 spaced from the wall section or fixed slat 20. The ends of the slats 24 and 25, because of the last named cut-out portion, are of a length such that they will project between the spaced apart vertical slats forming the side walls 18 to hold the transverse partition, or partitions, in position.

It will be seen that the transverse partitions can readily be put in place because of their flexibility and this is done in such a manner that the slots 27 in the slat 25 on the transverse partition engages the vertically arranged longitudinal partition 23 thereby holding it in spaced apart relation with respect to the slat 20 to provide the above described feed trough. Obviously, the transverse partition need not be made of slats but can be made of a single piece or any other suitable arrangement of parts which will accomplish the function of a separating transverse partition as well as an interlocking arrangement to hold the vertically disposed longitudinal partition 23 in place.

There is also provided one or more removable water troughs 29 which are placed within the feed troughs 22. Preferably these consist of rectangularly shaped receptacles having bottom, side and end walls. They may be placed in the feeding trough in such a manner that the legs 26 of the transverse partition extend downwardly therein to rest on the bottom wall and hold it against the floor of the crate. Also, one of the side walls of the water trough will enter the slot 27 together with the feed trough slat 23 in such a manner that both water trough and feed trough walls are interlockingly engaged by the transverse partition. The slot 27 will be of such width so that it will easily engage both the longitudinal partition or slat 23 and the wall of the watering trough without binding. This will permit the water troughs to be moved back and forth to the extent of their end walls so as evenly to divide the watering area and feeding area between partitions and facilitate an even distribution of feed and water.

There are many advantages to the improvement embodied in the present construction. Such a crate with the present feed and water trough arrangement will assemble easily because all parts are so fabricated as to be combined and folded into one strong unit without

the addition of staples, wires, or nailing of any kind other than the wires which are part of the mat. The partitions are so constructed as to provide maximum strength without additional bracing. The watering trough preferably is made of wax paper but may be made of plastic, glass, metal, rubber, or any other suitable material. The water trough and the feed trough are held solely in position by the upright transverse partition because of the interlocking engagement of the slotted portion of the bottom strip of the latter. This arrangement permits ready feeding and watering of livestock regardless of distances, and also permits easy access for replacement of feed or water en route. The transverse partitions keep the stock from crowding and thereby substantially reducing the danger of smothering. Several varieties of livestock can be shipped in one crate with each variety being kept separate, thereby tending considerably to eliminate physical damage to the stock. The partitions divide the stock load into smaller units and prevent the entire weight of the contents of the crate from shifting from one section to another.

It will thus be seen that the objects hereinbefore set forth can readily and efficiently be attained, and since certain changes may be made in the above article and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described our invention what we claim as new and desire to secure by Letters Patent is:

1. In a shipping container for livestock having secured-together pairs of side and end walls, a floor and a cover member, the improvement comprising a removable longitudinal partition arranged along said floor between the end walls and resting directly on said floor in spaced relation with respect to the side walls to provide a feeding trough, and a removable transverse partition spaced above said floor, the ends of which are mounted in apertures in the side walls, said transverse partition being slotted and interlockingly engaging at the slot thereof said longitudinal partition to hold the same in erect and spaced apart position with respect to said side walls.

2. In a shipping crate for livestock having secured-together pairs of side and end walls, a floor and a cover member, the improvement comprising a removable longitudinal partition arranged along said floor between the end walls and in adjacently spaced relation with respect to one of the side walls to provide a feeding trough, a removable watering trough comprising a container having bottom, side and end walls disposed between said one side wall and said longitudinal partition, a removable transverse partition whose ends are mounted in apertures in the side walls, said transverse partition being slotted and interlockingly engaging at the slot thereof said longitudinal partition and also an adjacent side wall of said watering trough, thereby to hold said longitudinal partition and said trough in position.

3. In a poultry shipping crate having secured-

70

together apertured side walls formed by spaced apart slats, end walls, a floor and a cover member, the improvement comprising a longitudinal partition removably located between the end walls and in spaced relation with respect to one of the side walls to provide a feed trough, a partition having legs secured thereto inwardly to the ends thereof, said ends projecting between said spaced apart slats constituting said side walls, a watering trough having bottom, end and side walls located between said longitudinal partition and said crate side wall, one of said partition legs resting on said bottom trough wall to hold it against the floor of said crate, and said transverse partitions being slotted to interlockingly engage said watering trough and also said longitudinal partition inwardly of the ends of the latter, thereby to hold the longitudinal partition vertically and in parallel spaced apart position with respect to said one side wall and to maintain said watering trough in position in the feed trough.

4. A shipping crate comprising pairs of opposed, apertured side and end walls and a bottom, a trough extending longitudinally between one pair of said walls comprising an elongated partition member disposed between said one pair of walls and resting upright directly on said bottom in laterally spaced relation to the other pair of walls, the bottom of said crate constituting the bottom of said trough, and a transverse partition member disposed normal to said first named partition member and in spaced relation above the bottom of the crate, said transverse partition member being releasably engaged with said first named member.

5. A shipping crate comprising pairs of opposed, apertured side and end walls and a bottom, a feed trough extending longitudinally between one pair of said walls comprising an elongated partition member disposed between said pair of walls and resting upright on said bottom in laterally spaced relation to the other pair of walls, a wall of said other pair having an elongated upright member secured thereto in parallel, laterally spaced relation to said first named member and coacting with the latter in defining said

trough, the bottom of said crate constituting the bottom of said feed trough, a separate watering trough disposed in said feed trough, and a transverse partition member disposed normal to said first named partition member, said transverse partition member being releasably engaged with said first named member and said watering trough.

6. A shipping crate comprising pairs of opposed, apertured side and end walls and a bottom, a feed trough extending longitudinally between one pair of said walls comprising an elongated partition member disposed between said one pair of walls and resting upright on said bottom in laterally spaced relation to the other pair of walls, a wall of said other pair having an elongated upright member secured thereto in parallel, laterally spaced relation to said first named member and coacting with the latter in defining said trough, the bottom of said crate constituting the bottom of said feed trough, a separate watering trough disposed in said feed trough and a transverse partition member disposed normal to said first named partition member and extending through the aperturing of said walls, said transverse partition member being provided with a slot of sufficient width to enable the same to be releasably engaged with said first named member and said watering trough and thereby hold the same in place.
